HEAT CONTROL

Gregory Pervelis, New York, N. Y.

Application November 9, 1939, Serial No. 303,585

7 Claims. (Cl. 236—91)

This invention relates to an improved control for steam heating system wherein the parts automatically function to maintain a desired temperature.

An object of the invention is to provide a heat control adapted to open a valve for the entrance of steam in proportion to the combined action of thermostats and a clock mechanism.

Another object of the invention is to provide a heat control wherein a pair of outside thermostats and a return water thermostat are used for varying the time in which steam is allowed to enter the heating system, the same cooperating with time control members.

An additional and more specific object is to provide a heat control for steam heating systems for buildings wherein there is provided a valve controlling the entrance of steam into the building and means for fully opening the valve from time to time controlled by the combined action of a clock mechanism and the action of one or a plurality of outside thermostats and a single inside thermostat, whereby the valve may be left open longer or shorter times with the steam fully on according to the heating needs of the building.

In the accompanying drawings—

Fig. 1 is a diagram showing part of a building and heating system and control therefor, disclosing an embodiment of the invention;

Fig. 2 is a diagram showing the control system illustrated in Fig. 1;

Fig. 3 is a sectional view through the motor housing illustrated in Fig. 1 and disclosing most of the parts in elevation;

Fig. 4 is a sectional view through Fig. 3 approximately on the line 4—4;

Fig. 5 is an elevation of the switch mechanism shown in Fig. 3;

Fig. 6 is a sectional view through Fig. 5 approximately on the line 6—6;

Fig. 7 is a side elevation of the switch mechanism shown in Fig. 5 but looking at the same from the opposite direction;

Fig. 8 is an elevation of a pair of clock actuated brushes and associated parts embodying certain features of the invention;

Fig. 9 is an elevation of one of the switch members shown in Figs. 5 and 7;

Fig. 10 is a hand controlled disk and arm for varying the action of the automatic controls;

Fig. 11 is a perspective view on an enlarged scale of the structure shown in Fig. 5;

Fig. 12 is a sectional view through Fig. 11 approximately on the line 12—12;

Fig. 13 is a fragmentary sectional view showing how the brushes of Fig. 8 engage the contacts of the switch shown in Fig. 11;

Fig. 14 is a perspective view of the switch member shown in Fig. 9;

Fig. 15 is an elevation of the insulating base or disk of the switch shown in Fig. 11;

Fig. 16 is a diagram showing a slightly modified arrangement of the control circuit;

Fig. 17 is a diagram similar to Fig. 16 but showing the part in a different position.

Referring to the accompanying drawings by numerals, and particularly to Fig. 1, 1 indicates a pipe for supplying steam under desired pressure. A hand controlled valve 2 is preferably provided in this pipe so as to permanently turn on or off the steam as may be desired. An automatically actuated valve 3 is also provided in the pipe 1 between the valve 2 and the upright 4 which supplies the various radiators with steam. It will be understood that there may be one or many uprights 4, all for receiving steam through the pipe 1.

Then valve 2 is fully open, which is its normal position, the full head of steam is against valve 3. When the automatic control mechanism hereinafter fully described functions, valve 3 will be fully open so that the full pressure of steam will be on the uprights 4, whereby steam will be quickly forced to the most remote point in the building being heated. This pressure of steam will remain on as long as valve 3 is open. When the automatic control hereinafter described functions to close valve 3, it will completely close the valve so that no steam can pass. For instance, if the valve is open ten minutes the full head of steam is on all the supply pipes of the building and then the full head of steam is turned off. There is no reduction in pressure of the steam as the valve is quickly turned on and off. From the various radiators there are provided suitable return pipes 6 which discharge into a return container 7. The water from this container may be directed to the sewer or, if desired, may be recovered and used again.

To control the valve 3, there is provided a control system which is indicated in Fig. 1 as system 8. This system is provided with outside thermostats 9 and 10 and an inside thermostat 11 which extends into the return water in the container 7. A motor hereinafter fully described is positioned in the housing 12 and also a clock 13 is positioned therein. In addition, certain switches and other parts are positioned in the housing whereby current may be turned on and

off the system 8. The system 8 is connected to the motor 12, the clock 13, the switches and other parts in the housing 12, and to the valve 3. The system 8 is also connected to the hand controlled valve 2. The system 8 is connected to the motor 12, the clock 13, the switches and other parts in the housing 12, and to the valve 3. The system 8 is also connected to the hand controlled valve 2.

off to the winding of the solenoid 14. The solenoid 14 is connected with the reciprocating valve member 3' so that when the solenoid is energized this valve member will be raised and the valve 3 fully opened. When the solenoid 14 is deenergized the weight of the core of the solenoid quickly and automatically closes the valve member 3'. If desired, a spring could be used to assist in closing the valve member. By reason of this construction, when the temperature near thermostat 9 rises current will be supplied to the motor in housing 12, which will cause the valve 3 to close unless it is already closed. Also if the return water in the container 7 is too hot the thermostat 11 will function to supply current to motor in housing 12 for opening the circuit of the solenoid 14 whereupon valve 3 will be shut off. However, the functioning of the thermostat 11 may be varied by the action of thermostat 10. If the water is slightly too hot and the temperature near thermostat 10 is somewhat lower than near thermostat 9, the action of thermostat 10 will counteract the action of thermostat 11 and, consequently, the motor in housing 12 will not function. In a certain sense, the mean action of the three thermostats controls the mechanism which supplies current to the windings of solenoid 14. The clock 13 functions in connection with the motor above mentioned to provide current for the solenoid 14 for a certain number of minutes each half hour. The various circuits for the system 8 are shown in Fig. 2 and the various structures associated with the motor are shown in Figs. 3 to 15 inclusive.

Referring to Fig. 2, it will be seen that the thermostat 9 acts through an expansible member 15 for raising a pivotally mounted bar 16. This bar is pivotally mounted at 17 and continually rests on a point member 18 connected with the expansible member 15. A retractile spring 19 is connected to a fixed support 20 and to the end 21 of bar 16 so that said bar 16 will continually press against the pointed member 18 in a direction for contacting or collapsing the member 18. The member 18, pipe 18' and thermostat 9 are old and well known and form part of an ordinary thermostatic structure now on the market. A member 22, preferably of insulating material, is rigidly secured to the bar 16 and carries a metal contact 23 which continually engages resistance 24. When the gaseous matter in thermostat 9 expands, bar 16 will be raised and the contact 23 will be swung over, for instance, to the position shown in Fig. 2. If the temperature should be lowered the gaseous matter in the thermostat would contract and spring 19 would swing bar 16 in the opposite direction and, consequently, contact 23 would be swung to the right as shown in the drawings. As the temperature increased and decreased near thermostat 9, the member or arm 22 would swing back and forth in proportion to the variation in temperature.

The outside thermostat 10 and associated parts are constructed identically with thermostat 9 and associated parts and, therefore, will need no detail description as the same reference numerals may be used. However, the thermostat 10 is connected in the circuit in a different way from the thermostat 9. The resistance 26 of thermostat 10 are part of a closed circuit including a wire 25, solenoid 26, wire 27, balancing resistance 28, wire 29, solenoid 30 and wire 31 which leads back to the source of cur-

rent, and a contact 23' is connected to the opposite side of the source of current. By this construction, whenever the thermostat 10 varies the contact 23' will be swung one way or the other and will unbalance the solenoids 26 and 30. This will cause the cores 32 and 33 to move on their pivotal mounting 34. These solenoids are connected by a bar 35 and, therefore, move in unison. A contact arm 36 extends from bar 35 and normally is arranged half way between the terminals 37 and 38. These terminals are connected with the terminals of motor 39, which is a standard reversible motor, operated at any desired speed, as for instance 800 revolutions per minute. When the contact arm 36 engages terminal 37, the armature of motor 39 will rotate in one direction, and when the arm 36 is engaging terminal 38 the armature of motor 39 will rotate in the opposite direction. The shaft 40 is connected with the armature of motor 39 and on this shaft there is provided a train of gears 41. An arm 42, preferably of insulating material, is connected with the center of one of the train of gears, said arm having a metal contact 42 continually resting on the balancing resistance or potentiometer 28. By this construction whenever the circuit including solenoids 26 and 30 is unbalanced the motor 39 will rotate until the circuit is balanced. When that occurs solenoids 26 and 30 will move the arm 36 out of engagement with either the contacts 37 or 38, whereupon the motor 39 will stop.

It will be seen that the motor 39 is shown diagrammatically in Fig. 2 but is so proportioned that the armature will rotate approximately eight hundred or more times while the contact 43 is moved one-half inch more or less. A shaft 44 is connected with the shaft 40 and also rigidly connected to a disk 45. The connection between the shaft 44 and the disk 45 is eccentric so that as shaft 44 rotates there will be an eccentric motion by the disk or eccentric 45 for raising or releasing a lever 46 which is pivotally mounted at 47. A spring 48 is connected with the free end of lever 46 and is maintained under tension thereby. As the eccentric 45 rotates through an arc of 180 degrees, the spring 48 will be brought under tension or released of tension according to the direction of rotation of the eccentric. Spring 48 is also connected at 49 to a pivotally mounted bar 50. This bar is pivoted at 51 which is substantially central thereof.

The thermostat 11 is made similar to thermostats 9 and 10 and, consequently, is provided with a pointed member 52 which is raised and lowered as the thermostat functions. The end of the pointed member 52 continually presses against bar 50 approximately half way between the pivot pin 51 and the end 53. A U-shaped member 54 is rigidly secured to bar 50 between pivot pin 51 and end 53. This bar may be made of insulating or other material as well as bar 50 and to each leg of this bar there is provided a metallic member 55 and each of these members is provided with a contact arm 56. These arms engage, respectively, resistances 57 and 58 and slide thereover to vary the resistance in the circuit. When the parts are as shown in Fig. 2, the contact arms 56 are central of the resistance elements 57 and 58. If the thermostat 11 functions alone the arm 56 would shift one away from the other simultaneously. Sometimes the action of the thermostat 10 cancels the action of thermostat 11 so that the result would be that the contact arms 56 would remain stationary. When

these arms do move, however, the circuit is unbalanced and the solenoids 59 and 60 will become unbalanced. When this occurs the bar 61 will swing the arm 62 which is rigidly secured thereto so that this arm, which is of metal, may engage either contact 63 or 64. When this occurs the motor 65 will be energized and will rotate either to the right or left according to which way arm 62 has moved. The motor will naturally rotate the armature and to this armature is secured a shaft 66. Shaft 66 rotates a small pinion 67 meshing with pinion 68 to which a shaft 68' is connected. Shaft 68' is connected to a pinion 69 for rotating the same. Pinion 69 is part of a train of gears 70, one of which is connected at 71 to arm 72. The gears 67 and 68 form a train for reducing the speed of the armature. This train of gears may have two gears or as many more as desired so that the gear wheel 73 secured to shaft 68' will rotate at a very much less speed than the armature of motor 65. As an example, the armature of motor 65 may rotate 800 or 900 revolutions per minute and in the same time gear wheel 73 will rotate a quarter or a half revolution. Preferably the train of gears 70 is such that the arms 72 will move even more slowly than the gear wheel 73 so that the metal contact arm 74 may move over the balanced resistance or potentiometer 75 rather slowly until the circuits for the solenoids 59 and 60 are balanced. The arm 72 may be of insulating material but the contact arm 74 must be of metal.

By reason of the construction just described, whenever any of the thermostats 9, 10 and 11 function the circuit of the solenoids 59 and 60 may be unbalanced and if unbalanced the motor 65 will rotate until the contact arm 74 moves sufficiently to again balance the circuit. During the movement of the arm 72 to balance the circuit, gear wheel 73 will rotate and will rotate the second gear wheel 76 which is continually in mesh therewith and which is preferably of the same diameter.

In Figs. 3 to 9, inclusive, will be seen details of the gear wheels 76 and associated parts. Referring particularly to these figures, it will be observed that the gear wheel 76 carries a switch which coacts with a clock 77. Clock 77 is a standard clock and the shaft 78 is rigidly connected with the minute-hand shaft of the clock so that it will rotate once each hour. A pair of brushes 79 and 80 are connected together at 81 and also rigidly connected to the arm 82 which is rigidly secured to shaft 78. By reason of this construction, the brushes 79 and 80 complete one rotation every hour. These brushes coact with a metallic ring 83 and with contact sections 84 and 85 of a switch element 86. The switch element 86 is formed of a sheet of metal having a central ring 87 offset at 88 and 89 with the offset portions merging respectively into the contact sections 84 and 85. A block of insulation 90 is riveted, cemented or otherwise rigidly secured to plate 87 and by reason of the set screw 91, shown in Fig. 6, is rigidly secured to a sleeve 92. Sleeve 92 is rotatably mounted on a shaft 93, which shaft has a block 94 rigidly secured thereto by a set screw 95. Block 94 is riveted, cemented or otherwise rigidly secured to a switch piece or disk 96 of insulating material. The metal contact ring 83 is riveted, cemented or otherwise rigidly secured to a base 96 so as to continually move therewith. This base is cemented, riveted, or otherwise rigidly secured to the gear wheel 76. A lead-in wire 97 is connected

with the plate 87 and a lead-in wire 98 is connected with the ring 83. The brushes 79 and 80 act merely to short-circuit or connect the switch element 86 with the switch element or ring 83. The brushes 79 and 80 are provided with contact ends 79' and 80' which engage the respective contact elements when in use. It will be observed that the contact 80' continually engages ring 83 but the contact 79' engages the respective contact sections 84 and 85 for a short period of time and the remaining time contacts with part of the base 96. As the brushes 79 and 80 make one complete circle in each hour, brush 97 will engage a portion of the respective contact sections 84 and 85 each half hour. Wires 97 and 98, as shown particularly in Fig. 6, extend to the valve 3 and are connected to the windings of solenoid 13, whereby whenever brush 79 is in contact with either of the sections 84 or 85, current will be supplied at 110 volts or at other standard voltage to the solenoid 14, whereupon it will quickly open and hold open valve 3 as long as brush 79 is engaging either contact 84 or 85. Preferably the current to the remaining part of the circuit is supplied at a much less voltage, as for instance 24 volts, by reason of the transformer 99.

When the device is first installed, the parts may be arranged as shown in Fig. 5, which will cause the indicating pointer 100 (Fig. 10) to point at the legend "10". This will indicate that a sufficient part of the respective sections 84 and 85 are exposed, as shown in Fig. 5, to permit the brush 79 to contact therewith for ten minutes each half hour. This will cause the valve 3 to remain fully open ten minutes for each half hour.

If the circuit shown in Fig. 2 should be unbalanced as heretofore described by a lowering of the temperature exterior of the building or a lowering of the return water to the thermostat 11, motor 65 would function to rotate the gear wheel 73 and also gear wheel 76. This rotation would be in a direction indicated by the arrow 101 (Fig. 5). This will move the pointer 100 in Fig. 10 toward the legend "15" and will expose more of the contact sections 84 and 85, whereby the brush 79 will engage these sections for a longer time each half hour. For instance, if the movement has been sufficient to swing the pointer 100 to a position opposite legend "15," it will mean that the contact of brush 79 with the contact sections 74 and 75 will be for a fifteen-minute period each half hour and, consequently, for each half hour valve 3 will be fully opened for fifteen minutes. If this should produce too much heat in a building, the return water would cause the thermostat 11 to function and upset the balance of the circuit so that motor 65 would rotate in the opposite direction and the gear wheel 76 would rotate in the opposite direction, whereby some of the exposed portions of the sections 84 and 85 would be withdrawn so that the contact with the brush 79 would be of less duration each half hour. The maximum rotary movement of the wheels 73 and 76 is through an arc of 180 degrees.

If sufficient steam is not provided through the structure just described, anyone may grasp the disk 102 shown in Figs. 3 and 10 and rotate the same in a direction to expose more of the contact sections 84 and 85, whereupon the valve 3 would remain open for a greater length of time during each half hour period.

By reversing the rotation of the disk 102, a reverse action can be secured. The disk 102 is

rigidly secured to the sleeve 92 which, as shown in Fig. 6, is rigidly secured to the switch member 96 and, consequently, the contact sections 94 and 95 may be moved to expose more or less of the same even if the gear 16 and base 96 are stationary. However, this manual positioning of the parts remains permanent until manually changed, whereas if the base 96 for exposing more or less of the contact sections 94 and 95 is automatically moved by the action of the thermostats the temperature changes may cause a reverse or return movement of base 96. The sleeve or tubular shaft 92 extends through a bearing 103 which is clamped in position by clamping screws 104. These screws are tightened sufficiently to provide a desired friction on the sleeve 92 so that it will not rotate unless some appreciable torque is brought to bear thereon, whereby shaft 92 may freely rotate without the friction against sleeve 92 in any way molesting the position of sleeve 92.

It will be observed that the base 96 is provided with slits or openings 105 (Fig. 15) and 106 through which the respective sections 94 and 95 move. The base 96 may be rubber, Bakelite, or other insulating material, and is cut away in arc-shaped lines 107 and 108 and along lines 109 and 110, whereby resilient tongues 111 and 112 are provided so as to yield sufficiently to allow a free sliding movement of the arc-shaped sections 94 and 95 of the switch element 86.

As shown in Fig. 10, the casing 12 is provided with an indicating arrow 113 and the words "Increase" and "Decrease" 114 and 115, whereby the superintendent of the building or other operator may readily understand which way the parts are to be turned for manually setting the parts for increasing the temperature in the building or decreasing the same.

When the parts are first installed, the pointer 100 is manually positioned, as well as the remaining parts, and the disk 102 is positioned with the zero mark opposite pointer 103. The automatic action of certain parts is adapted to swing the pointer 100 one way or the other, but the automatically acting parts will not move the disk 102 which is moved only by the hand of an operator. It will be readily understood, of course, that if desired the pointer 100 and associated parts could be set at a new position by hand at any time, though ordinarily it is left in its original setting and the desired results are secured by manually rotating disk 102 which rotates the switch element 86 shown in Fig. 9.

If the control arrangement were functioning and the parts were arranged as shown in Fig. 2 and the temperature exterior of the building should lower either slowly or suddenly, the thermostats 9 and 10 would be affected but the thermostat 11 probably would not be affected to any appreciable extent. When the thermostats 9 and 10 are affected by a lowering in temperature, the respective pointed members 12 will move downwardly by reason of the action of the respective springs 18. This will swing the contact blades 23 and 23' to the right, as shown in Fig. 2, and will immediately upset certain circuits.

Referring particularly to the thermostat 10 and associated parts, when the arm 23' moves to the right the circuit including the solenoids 26 and 30 are upset and current will flow from the supply wire 116, through wire 31 to the solenoid 30, wire 29, contact member 43, resistance 28, wire 117, solenoid 26, wire 28, resistance 24', arm 75

23' and wire 118 back to the supply wire 116. Current flowing in this circuit will cause the arm 36 to swing and thereby close the circuit of the motor 39. This motor is supplied with current from the supply wires 119 and 126, which may be connected with the supply wires 116 and 116', or any other suitable source of current. As motor 39 functions it will swing the arm 43 downwardly, as shown in Fig. 2, until the circuit is again balanced. At the same time, it will partly rotate the eccentric 46 and will bring the spring 48 under greater tension. If the return water remains at the same temperature, thermostat 11 will remain stationary but as the spring 48 has been brought under greater tension the bar 50 will be swung for swinging the arms 56 to the right and thereby unbalance the circuit of which these arms are a part. At the same time these things occur, arm 23 has moved to the right so that the circuit which includes the resistance 24 and the resistances 57 and 58 is unbalanced, and current will flow through the solenoids 59 and 60 for switching on current from a suitable source, namely, from wires 116 and 116', whereby motor 65 will rotate and move the various parts heretofore described for swinging the arm 72 to the right sufficiently to again balance the circuit. While this arm is swinging, gear wheels 73 and 76 will function and certain other parts as above described.

During the unbalanced period of the circuit, including solenoids 59 and 60, current will pass from the supply wire 116 through wire 121 to contact arm 23, and will split at this point, some current passing through the wire 122 and the remaining part passing through wire 123. If the arm 23 is positioned as shown in Fig. 2, some of the current will pass through wire 123, then through wire 122, by means of the extra resistance inserted in wire 122 by reason of the position of arm 23. Current passing through wire 122 will pass through the resistance 58, arm 55, wire 124, solenoid 60, wire 125, part of the resistance or potentiometer 75, arm 74 and wire 126 back to the source 116'. The current passing from arm 23, through wire 123, will pass through the resistance 57, contact blade 66, wire 127, solenoid 59, wire 128, part of the resistance 75, contact arm 74 and wire 128, back to wire 116'. As more current will pass through one of these circuits, then the other one of the solenoids, as for instance solenoid 59, will receive more current than solenoid 60 and, consequently, bar 61 will be tilted for causing arm 62 to engage contact point 68, whereby motor 65 will rotate in one direction. If more current should pass through wire 122 and parts connected therewith, arm 62 would swing against contacts 64 and cause motor 65 to rotate in a reverse direction. The current for motor 65 is conducted by wire 129 from wire 121 to arm 62 and then through the motor and from the motor through wire 130 back to wire 116'.

In Figs. 16 and 17 a slightly modified structure is provided to take the place of the thermostats 9, 10 and 11 and associated parts. As indicated in Fig. 16, the thermostat 131 is the same as thermostat 11, but instead of being connected in the circuit, as shown in Fig. 2, the thermostat is mechanically connected by a rod 132 to arms 133 and 134. These arms coact with resistances 135 and 136, which resistances are connected to the end of control potentiometer or resistance 137. An arm 138 coacts with the resistance 137 and is actuated by a rod 139 moved by and outside ther-

mostat 140. When the temperature rises or falls, the thermostat 140 will function to unbalance the circuit by shifting arm 138, so that the parts heretofore described will function. However, if the temperature outside of the building remains stationary and there is a change in the temperature of the return water, thermostate 131 will function to swing the arms 133 and 134, for instance to the position shown in Fig. 17. This will unbalance the circuit without any action of the thermostat 140. It will be understood that the wires 125 and 128 are the same as in Fig. 2 and the remaining parts are the same as in said figure, the only difference being in the parts above the solenoids 59 and 60.

I claim:

1. A heat control for a steam heating system for a building including an automatically closing valve for turning off steam to said system, a solenoid for opening and maintaining open said valve, a switch for turning on current to said solenoid, said switch being provided with a pair of contact members, one of which is a circle and the other an arc-shaped member and a brush for connecting the contact members, said brush having one arm in contact with the circular contact member and a second arm positioned to be moved into and out of contact with said arc-shaped contact member, a clock for moving said second arm into engagement with said arc-shaped contact member, maintaining said second arm in engagement with said arc-shaped contact member for a predetermined period and then moving the second arm out of engagement with said arc-shaped contact member, and thermostatically operated means for moving said arc-shaped contact member for varying the time period that said second arm engages the same.

2. A heat control for a steam heating system for a building including an automatically closing valve for turning off steam to said system, a solenoid for opening said valve and maintaining the same open for a predetermined period of time, a switch for turning on current to said solenoid, said switch being formed with spaced contacts and a brush for connecting said contacts, a clock for moving said brush into engagement with said spaced contacts, maintaining the brush in engagement with the spaced contacts a predetermined time and then moving the brush out of engagement with the spaced contacts, a primary thermostat positioned exteriorly of said building, an auxiliary thermostat utilizing the temperature of the return water from the heating system, and means capable of being actuated by the conjoint operation of said thermostats to control the movement of said spaced contacts with respect to the brush for varying the time period that said brush engages said spaced contacts.

3. A heat control for a steam heating system for a building including an automatically closing valve for turning off steam to said system, an electrically actuated member for opening said valve and maintaining the same open a predetermined period of time, a switch for turning on electric current to said electrically actuated member, said switch being formed with spaced contacts and a brush structure for electrically connecting the spaced contacts, a clock for moving said brush structure continually at an even pace into engagement with said spaced contacts, maintain the brush structure in engagement with the spaced contacts a predetermined period of time and then move the brush structure out of

engagement with the spaced contacts, electrically actuated power structure for moving said spaced contacts in respect to said brush structure for varying the time period that said brush structure engages said spaced contacts, a circuit for said power structure including a reversing switch, and means for opening and closing said switch; and a thermostat for causing said means to function to close the reversing switch in one direction when the temperature near said thermostat rises and close in the opposite direction when the temperature lowers whereby said brush structure is caused to engage said spaced contacts for a greater or less time period as the temperature near the thermostat rises or falls.

4. A heat control as specified in claim 3 characterized by the use of a second thermostat actuated by the temperature of the return water from said heating system when the return water is above or below a certain temperature, said second thermostat acting to cause said means to function sooner or later to close said reversing switch as the temperature of the return water rises or falls.

5. A heat control as specified in claim 3 characterized by the use of a second thermostat actuated by the temperature of the return water from said heating system when the return water is above or below a certain temperature, said thermostat when functioning acting to cause said means to function and close said reversing switch sooner or later as the temperature of the return water rises or falls and a third thermostat exposed to the atmosphere exteriorly of the building positioned to cause said means to function and close said reversing switch sooner or later as the temperature near said third thermostat rises and falls.

6. A heat control for a steam heating system for a building including an automatically closing valve for turning off steam to said system, an electrically actuated structure for opening said valve, a circuit for said electrically actuated structure including a switch having a pair of spaced contacts and a brush structure for electrically connecting said spaced contacts, said spaced contacts comprising a continuous ring and a switch element having a pair of spaced electrically connected arc-shaped members, said ring and said arc-shaped members being positioned concentrically, said brush having a pair of resilient prongs, one of said prongs being adapted to continually engage said ring and the other of said prongs being adapted to successively engage said arc-shaped members, an insulating base rigidly secured to said ring and provided with a pair of slots through which said arc-shaped members protrude so as to be engaged by one of the prongs of said brush structure, a clock connected with said brush structure for moving the contact ends thereof in a circle in a given period of time, and thermostatically controlled means for partly rotating said base to expose more or less of said arc-shaped members.

7. A heat control for a steam heating system for a building including an automatically closing valve for turning off steam to said system, an electrically actuated member for opening said valve and maintaining the same open a predetermined period of time, a switch for turning on electric current to said electrically actuated member, said switch being provided with spaced contacts, one of said contacts being circular and the other being arc-shaped, a brush structure coacting with said contacts, said brush structure being

provided with an arm constantly engaging said circular contact and a second arm for engaging said arc-shaped contact, clock mechanism for moving said brush structure at an even pace, said clock mechanism moving said brush structure so that said second arm will be in engagement with one or the other of said arc-shaped contacts a predetermined period of time and then out of engagement therewith, a primary thermostat exteriorly of said building on one side, a second 10

thermostat exteriorly of said building on the opposite side to said primary thermostat, a third thermostat actuated by the temperature of the return water from said system, and means capable of being actuated by each of said thermostats for causing more or less of said spaced contacts to engage said second arm for varying the duration said second arm is in engagement with said spaced contacts.

GREGORY PERVELIS.
